UNITED STATES PATENT OFFICE.

LOVANE MASON AND CHARLES B. SHAVER, OF GASPORT, NEW YORK.

CRATE.

SPECIFICATION forming part of Letters Patent No. 374,612, dated December 13, 1887.

Application filed September 3, 1887. Serial No. 248,720. (No model.)

To all whom it may concern:

Be it known that we, LOVANE MASON and CHARLES B. SHAVER, citizens of the United States, residing at Gasport, in the county of 5 Niagara and State of New York, have invented certain new and useful Improvements in Crates; and we do declare the following to be a full, clear, and exact description of the invention, such as will enable others skilled in the art to 10 to which it appertains to make and use the same, reference being had to the accompanying drawings, and to the letters and figures of reference marked thereon, which form a part of this specification.

15 The object of our invention is to provide a light crate for the transportation of fruit, &c., said crate being sufficiently strong and constructed at such small cost as to be given away by the shipper.

20 The nature of our invention will be described below, and pointed out in the claims.

In the drawings, Figure 1 is a perspective, the cover removed. Fig. 2 is a plan view, the cover removed. Fig. 3 is a broken perspective of the cover. Fig. 4 is a longitudinal vertical section, the cover removed.

Like letters refer to like parts.

The material used is wooden stripping about one-eighth of an inch thick, and bass-wood 30 will answer the purpose well. Where said stripping turns a corner, it is cut or scored nearly through, so as to bend easily without breaking or splitting, and where there are two or more thicknesses they are held together by 35 tacks, the points of which may be bent in.

A crate may be made up as follows: The strip *a* forms a part of an end, *A*, of the box, is then bent at right angles and forms a side, *B*, and is again bent at right angles and extends 40 half across the other end, *A'*, of the box. Under the last-mentioned bend of *a* the strip *b* extends entirely across the end *A'* of the box, is then bent at right angles and forms side *B'*, and is then bent again at right angles to overlap 45 the first-mentioned bend of *a* and form a portion of the end *A* of the box. The bottom *C* is formed thus: Take a single strip equal to the length of the bottom and the height of the two ends, cut the strip nearly through in two 50 places, which will form three sections, (see Fig.

4,) bend the end sections to a vertical position, and insert the whole inside of *a* and *b*. The middle section will then form a bottom proper, *C*, and the end sections inside linings, *c c*, for the ends *A A'*.

55 Below the center a wide re-enforcing strip, *D*, extends down one side under the bottom and partly up the other side, the free ends of this strip being held by a wooden strapping, *d*, which also extends entirely around the crate. 60 The cover *E* is made of two strips, *e e'*, one placed inside the other, the parts *e² e³* being bent down to form sides and ends. The said strips are tacked together and the free ends are held in place by inside and outside wooden 65 straps, *f f*.

A crate constructed as above will have two thicknesses at each end and an overlap from the side strip extending about one-half across each end, which will give to a portion of said 70 ends three thicknesses. The sides below the strap *d* are double, also the bottom, on account of strip *D*. The cover has a double top and single sides and ends. Though the crate will be light it will have ample strength, and at 75 the places where it is most needed. When the cover is fastened with basket-hooks or strings, it makes a perfect handle to carry by. The trade demands a "gift-crate," and our device meets the demand and at the same time 80 furnishes a crate strong enough to transport fruit, &c., to any distance. It will be understood that the crate is filled with wooden shelves and boxes, but it is not necessary to show them.

85 Having fully described our invention, what we claim, and desire to secure by Letters Patent, is—

1. The combination, with the stripplings *a* and *b*, each comprising an end and side portion, both side portions being horizontally overlapped, in full width upon opposite end portions to cover about one-half the width of the latter, of the strippling *C*, comprising a bottom portion and also two end portions extending upward inside of the end portions of *a* and *b*, and of a width substantially equal to that of the said end portions of *a* and *b*, as set forth.

2. In a crate, the combination, with the 100

strips *a* and *b*, bent to form the ends and sides and terminating in end overlaps at opposite corners, of the bottom forming strips *C*, having vertical extensions or end linings, *c*, the 5 re-enforce or double bottom *D*, and the wooden strap *d*, extending around the crate, as set forth.

In testimony whereof we affix our signatures in presence of two witnesses.

LOVANE MASON.
CHARLES B. SHAFER.
